REFRIGERATING APPARATUS

Lewis W. Eggleston, Davison, Mich., assignor to
Detroit Lubricator Company, Detroit, Mich., a
corporation of Michigan

Application February 27, 1939, Serial No. 258,597

23 Claims. (Cl. 62—101)

My invention relates generally to refrigerating apparatus and more particularly to those employing solid carbon dioxide as the cooling agent.

Much difficulty has been experienced in the past in keeping the desired low temperatures constant and evenly distributed throughout refrigerated compartments cooled by solid carbon dioxide due to the effect of the change in quantity as the solid carbon dioxide evaporates and escapes from the compartment.

An object of my invention is to provide a refrigerating system which is relatively uninfluenced by the quantity of solid carbon dioxide in the refrigerating system.

Another object of my invention is to provide an improved method of transferring heat from one compartment of a refrigerating apparatus to another compartment so that stratification of temperatures therein is prevented.

Another object of my invention is to provide an improved cold control means whereby the heat abstracting effect of the solid carbon dioxide is controlled to prevent an undesirable low temperature in the refrigerated compartments.

The invention consists in the improved construction and combination of parts, to be more fully described hereinafter and the novelty of which will be particularly pointed out and distinctly claimed.

In the accompanying drawings, to be taken as a part of this application, I have fully and clearly illustrated my invention, in which drawings—

Figure 1 is a view in elevation of the front of my refrigerating apparatus with a portion broken away to show my conduit system, and having a portion in section to show the construction of my compartments;

Fig. 2 is a view along the line 2—2 of Fig. 1 looking in the direction of the arrows but with the conduit system intact;

Fig. 3 is a view looking from the right end of the refrigerating apparatus with parts broken away to show the construction of the carbon dioxide compartment and one of the storage compartments;

Fig. 4 is a view of the weir member and accompanying cold controlling means;

Fig. 5 is a view of the weir member taken along the line 5—5 of Fig. 4 and looking in the direction of the arrows;

Fig. 6 is a view of the cold controlling means taken along the line 6—6 of Fig. 4 looking in the direction of the arrows, and

Fig. 7 is a view showing a modification of my invention.

Referring to the drawings by characters of reference the numeral 1 designates a rectangular, metallic cabinet having end walls 2, 3, side walls 4, 5, a bottom wall 6 and a top wall 7. A plurality of rectangular, metallic tubular members 8 are located within and spaced from the walls of the cabinet 1. The tubular members 8 preferably have their bottom ends closed and their top ends open and terminating below the top wall 7 of the cabinet 1. Each of a plurality of tubular throat members 9 has one end respectively secured in a suitable manner to the top end portions of the tubular members 8 and the top or other end portions extending through apertures in the top wall 7 of the cabinet 1 so that their marginal portions 10 are secured in a suitable manner about upturned flange portions 11 of the top wall 7 surrounding the apertures. The throat members 9 are preferably made of a suitable non-heat conducting material, such as rubber, so that heat transfer from the top wall 7 to the members 8 is held to a minimum. The tubular members 8 cooperate respectively with the throat members 9 to form a plurality of compartments 12, 13, 14 and 15. The open upper ends of the throat members 9 may be closed by suitable cover or lid members (not shown) to prevent external air from circulating into the compartments 12, 13, 14 and 15 and thereby further introducing heat to the compartments.

The compartments 12 and 13 are located adjacent to but spaced from the end walls 2 and 3 respectively, and the compartments 14 and 15 are secured together and located intermediate but spaced from the compartments 12 and 13. The adjacent top portions of the compartments 12 and 15, and 13 and 15, are secured together by means of U-shaped, metallic members 16, 17 respectively. The metallic members 16, 17 are preferably made of a metal having a high rate of heat conduction, such as copper or aluminum, so that heat may be conducted therethrough from the compartments 12, 13 to compartment 15. The adjacent walls of the compartments 14, 15 are separated by a piece of insulating material 18, such as Celotex, with the exception of a small metallic connection at the top portions of their respective tubular members 8, at which portions they are connected together by means of rivets 19, intimately securing together the tubular members, and a rectangular, metallic spacer member 20. In this manner I secure all of the

top portions of the tubular members 8 together in heat exchange relation. The compartment 15 is the refrigerating compartment and is designed for receiving suitable solid refrigerant medium such as solid CO₂, while the compartments 12, 13 and 14 are the refrigerated compartments and are designed to receive perishable food products.

The compartments 12, 13 are also connected in heat exchange relation with compartment 15 by means of a refrigerant medium circulatory system, generally designated 21. The circulatory system 21 may comprise two interconnected conduits 22, 23 having upwardly extending end portions 22^a, 23^a respectively, secured to and communicatively connected to a hollow chambered member 24, to be described more completely hereinafter. The conduits 22, 23 preferably encircle the tubular members 8 of the compartments 12 and 13 respectively. The conduits 22, 23 have downwardly sloping portions 25, 26 respectively, adjacent the tubular member of the compartment 15, and upwardly sloping portions 27, 28 encircling the compartments 12, 13. The portions 27, 28 terminate in end portions 27^a, 28^a respectively, secured to and communicatively connected with the member 24 to provide for gravity circulation of a liquid heat transfer medium. Secured to the top portion of the member 8 of compartment 12 and intermediate the compartment 12 and the end wall 2 is a sheet metal member 29 which is preferably of copper or aluminum. The sheet metal member 29 extends downward along the side of and is secured to the tubular member 8 of compartment 12, and at its lower end portion turns outward and upward to receive, in good heat exchange relation, a conduit portion 29^a of the upwardly inclined portion 27 of the conduit 22. A sheet metal member 30 similar to the member 29 is secured to the upper end portion of the tubular member 8 of compartment 13, intermediate the compartment 13 and the end wall 3, and extends downward and outward to receive, in heat exchange relation, a conduit portion 30^a of the upwardly inclined portion 28 of the endless conduit 23 in a manner similar to that of the member 29. The portions of the inclined conduit portions intermediate the portions 29^a, 30^a and 27^a, 28^a respectively, are preferably secured in heat exchange relation to the adjacent portions of the tubular members 8 for additional cooling of the compartments 12, 13, respectively, and warming of the liquid medium in the system 21.

Secured in heat exchange relation to the bottom of the compartment 15 there is a sheet metal member 31 which is preferably of copper or aluminum. The member 31 is U-shaped and has a pair of parallel, upstanding leg portions 32, 33, one leg portion being on either side of the tubular member 8 of compartment 15. The upstanding portion 32 is intermediate the compartment 15 and the compartment 12, and the upstanding portion 33 is intermediate the compartment 15 and the compartment 13. The upstanding portions 32, 33 are each adjacent to but spaced from the vertical side walls of compartment 15 so that there is no direct conduction of heat to the upstanding portions 32, 33 except through the bottom end wall of compartment 15. The upper end portions of the upstanding portions 32, 33 preferably turn outward and downward and receive, in heat exchange relation, conduit portions 32^a, 33^a of the portions 25, 26 respectively.

The refrigerant medium circulatory system 21 contains a liquid medium which preferably has

a large coefficient of expansion, such as acetone or methanol, so that the volume thereof will change materially with change in temperature. The refrigerant medium, which in this case is preferably solid CO₂, in the compartment 15 extracts the heat from the sheet metal piece 31 through its conduction with the bottom wall of compartment 15. Due to the conductivity of the upstanding portions 32, 33 and the heat exchange relation with the bottom of the compartment 15, heat is extracted from the conduit portions 25, 26, respectively, and is absorbed by the CO₂ to cause evaporation thereof. Cooling of the conduit portion 32^a causes the portion of the liquid medium within the conduit portion 32^a to be lowered in temperature so that its density is increased. Upon increase in density of the liquid medium portion, the liquid medium will flow downward within the conduit portion 25 toward the portion 27, and as further liquid medium is cooled within the portion 32^a, the liquid within the conduit 22 will gradually circulate from the portion 32^a downward and upward through the portion 27 to the member 24, from whence it flows downward again to the conduit portion 25. As the cool liquid medium flows through the conduit portion 29^a it abstracts heat from the sheet metal member 29 which thereby increases the temperature of the liquid medium and lessens its density to aid in the natural circulation of the liquid medium through conduit 22. The sheet metal member 29 is thereby cooled by the circulating liquid medium so that it in turn cools the upper portion of the tubular member 8 of compartment 12 thereby refrigerating the compartment 12. In like manner the liquid medium is circulated through the conduit 23 removing heat from the compartment 13 and transferring it to the upstanding portion 33 to be finally transferred to the evaporating CO₂ within the compartment 15.

Circulation of the liquid medium through the circulatory system 21 is controlled by means of a temperature control apparatus, generally designated 50, of which the hollow chambered member 24 comprises a portion. The member 24 is the highest point of the circulatory system 21 and comprises a pair of oppositely disposed, downwardly projecting, tubular passageways 51, 52 which receive the upwardly extending portions 22^a, 23^a respectively of the conduits 22, 23 respectively. The upwardly extending end portions 27^a, 28^a are received in downwardly projecting, oppositely disposed, tubular passageways 53, 54 respectively, and which passageways 53, 54 are respectively parallel to passageways 51, 52. The passageways 51, 52 and 53, 54 form respectively the outlet and inlet chambers 55, 56 of the hollow member 24 and are preferably cast integral therewith. The outlet chamber 55 is separated from the inlet chamber 56 by a dam or weir member 57 so disposed within the member 24 that it is the path of any liquid medium which circulates through either of the conduits 22, 23. The dam member 57 acts upon a predetermined low temperature of the liquid medium in the circulatory system 21 to interrupt the natural circulation of the liquid in the conduits 22, 23 so that heat may no longer be extracted from the compartments 12, 13 respectively, and transferred to the compartment 15 by the circulatory liquid medium.

The average temperature at which the circulation of the liquid medium is prevented by the dam 57 is controlled by means of an adjustment means 58. The means 58 comprises a hollow

tubular member 59 of circular cross-section having end walls 60, 61. Secured in fixed position within the tubular member 59 is a hexagonal, nut-like member 62 which has a threaded central aperture 63 therethrough. The nut-like member 62 separates the tubular member 59 into upper and lower intercommunicating chambers 64, 65. Located within and having a slightly smaller cross-section than the lower chamber 65 is a liquid displacing member 66 having a central aperture 67 therethrough. A hollow, tubular, cylindrical, externally threaded member 68 extends upward through and in screw-threaded relation with the aperture 63 so that its upper end 69 is located within the chamber 64 and its lower end is within chamber 65. A friction member 70 which may be a flat, spring like member has its end portions 71 curled downwardly and inwardly so that the smooth, external curved surfaces frictionally engage the inner wall of the tubular member 59. The member 70 is secured in a suitable manner, as by screws 72, to the lower end wall 73 of the fluid displacement member 66 and has an aperture therethrough which registers with the central aperture 67 of the fluid displacement member 66. The lower end of the tubular member 61 extends downward through the central aperture 67 of the displacement member 66 and through the aperture in the friction member 70 and is suitably secured to the friction member 70, as by peening 73^a, so that rotation of the member 68 will cause rotation of the friction member 70 and the liquid displacement member 66, and will cause the members 66 and 70 to move vertically within the chamber 65. The end portion 69 of the member 68 has a slot 74 in which a suitable tool, such as a screw driver, may be inserted and used for rotating the tubular member 68 in the nut-like member 62 to position the liquid displacing member 66. The friction member end portions 71 act to prevent unwanted rotation of the member 66 so that the setting thereof is maintained.

A conduit 75 has one end 76 secured in fluid-tight relation within a central aperture in the end wall 60, and the other end 77 secured in fluid-tight relation to the lower wall of member 24 and communicating with the outlet chamber 55 so that the liquid medium within the member 24 is in communication with the chamber 65. A conduit 78 has one end 79 secured in fluid-tight relation to a fitting 80 located in the side wall of chamber 64 adjacent the end wall 61 so that conduit 78 is in communication with the chamber 64. The other end 81 of the conduit 78 is received within a top wall 82 of and in communication with the hollow member 24 and acts to equalize pressures within the member 24 and the tubular member 59 so that no liquid is caused to flow from or to the chamber 65 due to a difference of pressure between the adjustment member 58 and the system 21 so that the liquid level within the chamber 65 and the member 24 will be at all times maintained the same. The member 59 is vertically secured to the side wall 5 of the cabinet 1 by means of a clamping strip 83 and rivets 84 so that it is in heat exchange relation therewith. The member 59 is also secured with respect to the member 24 so that the liquid displacement member 66 may be moved by means of the tubular member 68 through the horizontal plane which passes through the top of the dam 57.

It is to be understood that the space intermediate the walls of the cabinet 1 and the walls 75

of the compartments 12, 13, 14 and 15 will be filled with a suitable insulating material so that the rate of heat transfer from the cabinet 1 to the compartments will thereby be lowered to a minimum. The compartments 12, 13 are particularly designed as a storage place for bulk ice cream, or the like. Compartment 14 is primarily designed for the storage of package goods, such as pre-packed ice cream. The compartment 14 will therefore preferably be run at a lower temperature than the compartments 12, 13 and its temperature is not adjustable by the temperature adjustment means 58. The compartment 14 is refrigerated by and is in good heat exchange relation with the refrigerated compartment 15 solely at the top portion thereof, through the rivets 19 and the rectangular metallic member 20, but the insulating material 18 which is preferably about $\frac{1}{8}$ of an inch thick may however allow a small amount of heat to be transferred from the compartment 14 to the compartment 15, throughout the entire height of the tubular member 8, but not such an amount as will unduly cool the compartment 14. It is to be understood that if lower temperatures are desired the material 18 may be made thinner or omitted. A central threaded aperture 85 in the end wall 61 is preferably closed by means of an externally threaded, bolt-like member 86 which is easily removable for adjustment. As is shown in Fig. 3 of the drawings, the adjustment means 58 is not connected to the top wall 7 of the cabinet 1 and access thereto is had through an aperture 87 in the top wall 7. This aperture 87 is preferably closed by means of a removable plug member 88 screwed to a threaded flange portion 89.

The liquid heat exchange medium which was described hereinbefore is introduced into the circulatory system 21 through the threaded central aperture 85 in the end wall 61 of the tubular member 59. The amount of liquid medium introduced to the system 21 is so proportioned that when the temperature of the compartments 12, 13 is lowered to the desired operating temperature, the liquid level of the system is substantially at the top portion of the dam 57. By so proportioning the quantity of liquid medium in the system 21 the natural circulation of the liquid medium through the conduits 22, 23 is prevented by the dam 57 when the temperatures of the compartments 12, 13 are at or lowered below the desired operating temperature. When the temperature of the compartments 12, 13 is above the desired predetermined temperature, the liquid medium in the circulatory system 21 expands, due to the inherent characteristics of the liquid medium, and overflows the dam 57 so that natural circulation of the liquid medium through the conduits 22, 23 occurs. The particular construction shown will also function to maintain the two compartments 12, 13 at substantially the same temperature. As one compartment warms up beyond that of the other for any cause whatsoever, the change in density of the liquid medium in the conduit system connected to the warmer chamber will be greater than that of the other system. For example, suppose that the chamber 12 warms up more than the chamber 13. The density of the liquid medium in the conduit portions 32^a, 33^a will be the same, both portions being maintained at substantially the same temperature by the compartment 15. Chamber 12 being at the higher temperature, conduit portion 29^a will be at a higher temperature than

conduit portion 30^a and therefore the density of the liquid medium in the portion 29^a is less than that in portion 30^a. As the rate of circulation of the liquid medium in the conduits 22, 23 is proportional to the differential in densities of the liquid medium therein, it is clearly seen that the liquid medium will circulate more rapidly in conduit 22 than in conduit 23, with a greater refrigerating effect, until the temperature of the container 12 is again brought substantially to that of the container 13. Because the U-shaped member 31 is in heat exchange relation solely with the bottom of the compartment 15, it may be seen that the temperature thereof will be maintained substantially constant regardless of the quantity of solid CO₂ which is contained within the refrigerated compartment 15. In this manner the variation in temperature of the tubular portions 32^a, 33^a, due to changes in quantity of the refrigerant medium, is prevented so that the temperature of the liquid medium within the circulatory system 21 will be maintained at a substantially constant temperature regardless of the quantity of solid CO₂ present.

Should it be desirable to change the predetermined temperature within the compartments 12, 13, the tubular member 68 may be rotated by means of a suitable tool, such as a screw driver, in the slot 74, so that the liquid displacement member 66 will displace more or less liquid depending upon whether it is desired to raise or lower the predetermined temperature to be maintained in the compartments 12, 13. It may readily be seen that if the liquid displacement member 66 is lowered so that it displaces more liquid within the chamber 65, the temperature at which the liquid medium must be lowered before the dam 57 will stop circulation within the circulatory system 21 will have to be substantially lowered, and if the liquid displacement member 66 is raised so that it displaces less liquid within the chamber 65, the predetermined temperature at which the liquid medium must be lowered is substantially higher.

The chamber 65 is in heat exchange relation with the side wall 5 of the cabinet 1, which side wall 5 will have a temperature which varies in accordance with the ambient temperature surrounding the cabinet 1. As the heat leakage from the medium surrounding the cabinet 1 to the compartments 12, 13 is dependent upon the differential in temperature between the ambient temperature and the temperature of the compartments 12, 13, and the ability of the circulating liquid medium to remove heat from the compartments 12, 13 is dependent upon the differential in temperature between the temperature of the liquid medium and the compartments 12, 13, it will be readily understood by those skilled in the art that to maintain a predetermined desired temperature within the compartments 12, 13 with increasing ambient temperature, the temperature of the liquid medium in the circulatory system 21 will have to be lowered in proportion to the increasing ambient temperature. In my invention, by maintaining the chamber 65 in heat exchange relation with the side wall 5 of the cabinet 1, I compensate for changes in ambient temperature by raising or lowering the temperature at which the natural circulation of the liquid medium in the circulatory system 21 is prevented. It will be seen that as the temperature of the side wall 5 and chamber 65 rises, the volume which the liquid will occupy in the chamber 65 will be increased and some of the liquid in the

chamber will flow through the conduit 75 to the circulatory system 21 and cause the average temperature thereof to be of necessity brought to a lower temperature before the dam 57 will act to stop natural circulation through the conduit system 21. Such a compensating effect acts in like manner as if an operator held a thermometer in one hand and manually adjusted the liquid displacement member with the other hand according to changes in ambient temperature read on the thermometer. In like manner, when the ambient temperature lowers, the temperature of chamber 65 will also be decreased so that liquid will be withdrawn through conduit 75 from the circulatory system 21, thereby rendering higher the average temperature within the circulatory system at which the dam means 57 stops natural circulation. I therefore provide means for maintaining a constant compartment temperature regardless of ambient temperature or of the quantity of solid CO₂ present. It is to be understood however that by varying the volume of chamber 65 I may over-compensate or under-compensate for changes in ambient temperature to secure any desired variation of compartment temperature with changes in ambient temperature.

In Fig. 7 I have shown a modification of my invention. The numeral 100 designates a substantially rectangular cabinet having an end wall 101, a front wall 102, and a top wall 103. Within the cabinet 100 and spaced from the walls thereof are two rectangular tubular members 104, 105. The tubular members 104, 105 have throat members 106, 107 respectively, secured in a suitable manner to the top end portions thereof. The throat members 106, 107 extend upward through apertures 108, 109 in the top wall 103 in a manner similar to the members 9 of Fig. 1. The tubular members 104, 105 are preferably made of a metal having good conductivity of heat and having their bottom end walls closed, and operate with the members 106, 107 respectively, to form compartments. The top portion of the tubular member 104 is connected by means of a metallic heat conducting member 109 to the top portion of the tubular member 105 so that the adjacent top portions of the tubular members 104, 105 are in heat exchange relation. The compartment formed by the tubular member 105 receives the solid refrigerant medium, which may be solid CO₂, and the compartment formed by the tubular member 104 is adapted to receive food products to be refrigerated, and which may be bulk ice cream. A conduit member 110 has its ends 111, 112 connected together at their high points by a chambered member 113 so that the chamber is adapted for natural convection flow of liquid medium. The conduit member 110 comprises an upwardly inclined portion 114 and a downwardly inclined portion 115. A portion 116 of the upwardly inclined portion 114 is secured in heat exchange relation to the lower end of a sheet metal member 117 which is in turn secured in heat exchange relation to the upper end portion of the tubular member 104 so that heat may be abstracted from the tubular member 104 and transferred to the conduit portion 116. A second portion of the portion 114, intermediate the portion 116 and the end 111, is preferably secured, as by soldering, in heat exchange relation with the adjacent portion of the tubular member 104. An L-shaped heat transfer metal member 118 has its horizontal portion 119 secured to the bottom end of the tubular member 105 and its ver-

tical portion 120 extending upward adjacent to but spaced from the side wall of the tubular member 105. The upper end of the vertical portion 120 is secured in heat exchange relation with a conduit portion 121 of the inclined portion 115. A dam or weir means 122 is interposed in the path of the circulating fluid through the conduit member 110 and is positioned in the hollow chambered member 113, and operates to prevent natural circulation of liquid medium through the conduit member 110 upon a predetermined mean low temperature of the liquid medium, in a manner similar to the dam 57 of Fig. 5. A temperature control apparatus 123, identical to the temperature control apparatus 58 of Fig. 4 is connected by means of conduits 124, 125 to the hollow member 113 in a manner similar to the way in which the conduits 75, 78 of Fig. 4 connect the temperature control apparatus 58 to the chambered member 24. The member 113 is preferably spaced from the members 105, 118 so that all of the conduit member 10 is cooled by conduction and radiation is inclined downwardly and is conducive to natural circulation.

The operation of the modification shown in Fig. 7 is as follows: The evaporating solid CO_2 extracts heat from the horizontal portion 119 of the L-shaped member 118, thereby extracting heat from the vertical portion 120. The vertical portion 120 extracts heat from the portion 121 of the conduit member 110 and the liquid medium contained in the portion 121 is cooled with a consequent increase in density. The heavy liquid medium is caused to flow by gravity downward through the inclined portion 115, after which the liquid medium flows upward through the inclined portion 114, abstracting heat from the conduit portion 116 and decreasing in density to further aid in the natural circulation of the liquid medium through the conduit member 110. The member 117 is in heat exchange relation with the tubular member 104 so that as the member 117 is cooled, the member 104 will likewise be cooled. As the average temperature of the liquid medium within the conduit member 110 is lowered, the volume thereof is diminished until the dam means 122 interrupts the flow of the liquid medium and further extraction of heat from the tubular member 104 is prevented. As the conduit portion 121 is maintained at substantially constant temperature by the solid CO_2 , which is in good heat exchange relation with the L-shaped member 118 solely at its horizontal portion 119, the volume of the liquid medium within the conduit member 110 will be directly proportional to the temperature of the tubular member 104 so that with constant setting of the temperature control apparatus 123, the average temperature of the tubular member 104, with constant temperature surrounding the cabinet 100, will be maintained substantially constant.

The temperature control apparatus 123 is in heat exchange relation with the side wall 102 of the cabinet 100 so that its temperature is proportional to the ambient temperature surrounding the cabinet, in a manner similar to that of the control apparatus 58 of Fig. 2. In this manner I vary the average temperature of the liquid medium circulating in the conduit member 110 in accordance with changes in ambient temperature surrounding the cabinet 100 so that the interior of the tubular member 104 is maintained substantially constant in temperature regardless of the ambient temperature.

I have shown a single system for each solid CO_2

containing compartment, but it is to be distinctly understood that two independent systems, such as is shown in Fig. 7, could be substituted for the interconnected system of Fig. 1, and in such a case the temperature of the compartments 12 and 13 thereof could be maintained at separate and independent temperatures at the will of the operator.

I have invented and herein disclosed a new and improved refrigerating apparatus which uses a solid refrigerant medium such as solid CO_2 , and which is operable to maintain temperatures within the refrigerated compartments substantially constant as long as any refrigerant medium is present in the refrigerant compartment. I have also set forth an apparatus which maintains substantially even temperatures throughout the interior of the storage compartments, due to the method of cooling the portions thereof, and have shown compensating means whereby the temperature of certain of the storage compartments is maintained constant irrespective of changes in ambient temperature. Furthermore, I have invented a novel means for adjustment of the predetermined desired temperature at which I maintain certain of the compartments.

What I claim and desire to secure by Letters Patent of the United States is:

- 30 1. In a refrigerating apparatus, a cooled compartment, a plate-like member having a high thermal conductivity, a cooling compartment spaced from said cooled compartment, heat transfer means including a heat transferring liquid medium connecting a bottom portion of said cooling compartment to said plate-like member, said plate-like member being on the top portion of the wall of said cooled compartment furthest away from said cooling compartment, and means for controlling the rate of heat transfer from said cooled compartment to said cooling compartment.
- 35 2. In a refrigerating apparatus, a cooled compartment, a cooling compartment spaced from said cooled compartment, heat transfer means connecting a bottom portion of said cooling compartment to the top portion of said cooled compartment, said top portion being on the wall of said cooled compartment furthest away from said cooling compartment, and means separate from said transfer means connecting the adjacent top portions of said compartments in heat exchange relation.
- 40 3. In a refrigerating apparatus, a cooled compartment having a top portion, a cooling compartment having top and bottom portions, conduit means adapted for natural convection flow of a liquid in heat exchange relation with said top portion of said cooled compartment and said bottom portion of said cooling compartment, a liquid medium in said means and having a substantial coefficient of expansion for flow through said means, and means separate from said conduit means connecting said compartments in heat exchange relation at said top portions thereof.
- 45 4. In a refrigerating apparatus, a conduit system adapted for gravity circulation of a liquid therethrough and having a high point, a cooling compartment having a bottom portion, a cooled compartment having a top portion, a portion of said conduit system being in heat exchange relation with said top portion of said cooled compartment, a second portion of said conduit system being in heat exchange relation with said
- 50
- 55
- 60
- 65
- 70
- 75

bottom portion of said cooling compartment; a liquid medium having a substantial coefficient of expansion upon increase of temperature, a weir means at said high point so that said medium is prevented from circulation through said conduit system when said medium is below a predetermined average minimum temperature, and reservoir means sensitive to ambient temperature surrounding the apparatus and operable to vary the quantity of said medium so that said cooled compartment is maintained at a substantially constant predetermined temperature irrespective of ambient temperature.

5. A refrigerated apparatus comprising a cooled compartment having a top portion, a cooling compartment having a bottom portion, conduit means in heat exchange relation with said top portion of said cooled compartment and said bottom portion of said cooling compartment, a liquid medium in said means having a substantial coefficient of expansion, reservoir means sensitive to ambient temperature surrounding the apparatus and communicating with said conduit means and controlling the quantity of said medium in said conduit means so that upon a predetermined low average temperature of said medium said high point is operable to regulate the flow of said medium in said conduit means, and a second cooled compartment adjacent said cooling compartment, said second compartment being in good heat exchange relation with the top portion solely of said cooling compartment.

6. In a refrigerating apparatus, a plurality of cooled compartments each having top portions, a cooling compartment having a bottom portion, said top portions being on the side of said cooled compartments furthest away from said cooling compartment, conduit means in heat exchange relation with said top portion of one of said cooled compartments and said bottom portion of said cooling compartment and having a high point, a second conduit means in heat exchange relation with said top portion of another of said cooled compartments and said bottom portion of said cooling compartment, said conduit means being interconnected at said high point to form a closed conduit system, a liquid medium in said system and having a substantial coefficient of expansion, and dam means at said high point so that expansion of said medium due to a temperature increase thereof above a predetermined average temperature in either of said conduit means will cause said expanded medium to overflow said dam means and circulate through said system, said medium when at an average temperature below said predetermined minimum temperature contracting and thereby being prevented from overflowing said dam means.

7. In a device of the character described, a cooled compartment having top portions, a cooling compartment having a bottom portion and a top portion, a conduit means, one of said cooled compartment top portions being on the side of said cooled compartment furthest away from said cooling compartment, the other of said cooled compartment top portions being adjacent said cooling compartment top portion, means having a high rate of heat transfer in heat exchange relation with said conduit means, said transfer means being in heat exchange relation with said one top portion, a second means having a high rate of heat transfer in heat exchange relation with said conduit means, said second transfer means being in heat exchange relation

with said bottom portion, a fluid heat exchange medium in said conduit means operable to transfer heat from said first transfer means to said second transfer means, and means connecting said cooling compartment top portion and said other top portion in heat transfer relation.

8. In an apparatus of the character described, a container operable to receive solid carbon dioxide, a storage container operable to store a substance at a predetermined low temperature, a liquid medium, conduit means containing said medium and adapted for natural convection circulation of said medium, a metallic plate having one end portion secured in heat exchange relation to said conduit means to remove heat from said medium and having the opposite end portion thereof secured in heat exchange relation with said first-named container, a second metallic plate having one end portion secured in heat exchange relation to said conduit means and having the other end portion secured in heat exchange relation to the top portion of said storage container on the wall thereof furthest away from said first-named container, means for controlling the circulation of said medium so as to maintain a predetermined substantially constant temperature of said storage compartment, and metallic plate means joining the adjacent top portions of said containers in heat exchange relation.

9. A refrigerating apparatus comprising a compartment to be refrigerated, a continuous conduit means having a portion thereof in heat exchange relation to said compartment, a liquid in said conduit means establishing a closed liquid circuit and operable to abstract heat from said compartment at said portion, means to abstract heat from said liquid at another portion of said conduit means, said liquid being expandable and contractible in accordance with the temperature thereof, said conduit means having a high point effective upon contraction of the liquid to interrupt the liquid circuit, means responsive to ambient temperature external of said refrigerated compartment to regulate the temperature at which said high point becomes effective, and means protecting said responsive means from temperatures in said refrigerated compartment.

10. In an enclosed fluid system adapted for natural convection cooling of a space, a liquid medium having a substantial coefficient of expansion, a conduit system having a high point, said system having a heat abstracting portion of relatively high temperature and having a radiating point of low temperature relative to said abstracting portion, dam means at said high point, said liquid medium being operable upon an increase in temperature to increase in volume and overflow said dam means so that said liquid medium will flow by natural convection in said conduit system, and means primarily responsive to ambient temperature external of the space to regulate the quantity of said medium within said conduit system in accordance with said ambient temperature, said means being so positioned and arranged relative to said abstracting portion as to be relatively uninfluenced thereby.

11. In an enclosed fluid system adapted for natural convection, a liquid medium having a substantial coefficient of expansion, a conduit system having a high point, said system having a heat abstracting portion of relatively high temperature and having a radiating point of low

temperature relative to said abstracting portion, dam means at said high point, said liquid medium being operable upon an increase in temperature to increase in volume and overflow said dam means so that said liquid medium will flow by natural convection in said conduit system, reservoir means sensitive to ambient temperatures external of the system and connected into said system and operable to control the predetermined temperature of said abstracting portion by the quantity of said medium therein in accordance with ambient temperature, and manually operable means operable on said reservoir means to regulate the quantity of said medium therein.

12. In an apparatus of the character described, a receptacle for the storage of a cooling medium and having a face with a plane surface, a cooled receptacle adjacent said first-named receptacle and having a face with a plane surface, said plane surfaces being spaced from and parallel to each other, means having a high rate of heat transfer connecting said plane surfaces at the top adjacent portions thereof, and means having a relatively low rate of heat transfer separating the remainder of said plane surfaces, said first-named means and said second-named means being so interrelated that said second-named receptacle is cooled by said first-named receptacle substantially without temperature stratification within said second-named receptacle.

13. In an apparatus of the character described, comprising a casing having a passageway therethrough, a weir means having a top face in said passageway, a chambered means, conduit means connecting the bottom portion of said chambered means to said passageway below the level of said top face, a second conduit means connecting the top portion of said chambered means to said passageway above the level of said top face, and means for varying the effective capacity of said chambered means below the level of said top face.

14. In an apparatus of the character described, comprising a casing having a passageway therethrough, a weir means having a top face in said passageway, a chambered means, conduit means connecting the bottom portion of said chambered means to said passageway below the level of said top face, a second conduit means connecting the top portion of said chambered means to said passageway above the level of said top face, and means adjustably supported within said chambered means for varying the effective capacity of said chambered means below the level of said top face.

15. In an apparatus of the character described, comprising a casing having a passageway therethrough, a weir means having a top face in said passageway, a chambered means, conduit means connecting the bottom portion of said chambered means to said passageway below the level of said top face, a second conduit means connecting the top portion of said chambered means to said passageway above the level of said top face, liquid displacing means having an upwardly extending portion, and a plate-like member having an aperture therethrough, said extending portion extending through said aperture and being operable to position said displacing means relative to said top face for varying the effective capacity of said chambered means below said top face.

16. In an apparatus of the character de-

scribed, comprising a casing having a passageway therethrough, a weir means having a top face in said passageway, a cylindrical member having upper and lower end walls, said end walls having apertures therethrough, conduit means having one end secured in said lower end wall aperture and communicating with the interior of said cylindrical member and having the other end thereof communicating with said passageway below the level of said top face, a second conduit means having one end secured within an aperture through said cylindrical member and connecting the top portion of said cylindrical member to said passageway above the level of said top face, a fluid displacing means having an upwardly extending portion, and a plate-like member having an aperture therethrough, said extending portion extending through said aperture and being operable to position said displacing means relative to said top face for varying the effective capacity of said cylindrical member below said top face.

17. In an apparatus of the character described, comprising a casing having a passageway therethrough, a weir means having a top face in said passageway, a cylindrical member having upper and lower end walls, said lower end wall having an aperture therethrough, conduit means having one end secured in said lower end wall aperture and communicating with the interior of said cylindrical member and having the other end thereof communicating with said passageway below the level of said top face, a second conduit means having one end secured within an aperture through said cylindrical member and connecting the top portion of said cylindrical member to said passageway above the level of said top face, a fluid displacing means having an upwardly extending portion, a plate-like member having a screw-threaded aperture therethrough, said extending portion having a screw-threaded section for cooperation with and extending through said screw-threaded aperture, said screw-threaded section being operable to be rotated within said screw-threaded aperture and being operable to position said displacing means relative to said top face for varying the effective capacity of said cylindrical member below said top face, and means for preventing unwanted rotation of said section.

18. In a refrigerating apparatus, a conduit system adapted for gravity circulation of a liquid therethrough and having a high point, a cooling compartment having a bottom portion, a cooled compartment having a top portion, a portion of said conduit system being in heat exchange relation with said top portion of said cooled compartment, a second portion of said conduit system being in heat exchange relation with said bottom portion of said cooling compartment, a liquid medium having a substantial coefficient of expansion upon increase of temperature, means at said high point so that said medium is prevented from circulation through said conduit system when said medium is below a predetermined average minimum temperature, and means sensitive to ambient temperature surrounding the apparatus and operable to vary the quantity of said medium so that said cooled compartment is maintained at a predetermined temperature relative to said ambient temperature.

19. In an apparatus of the character described, a container operable to receive solid carbon dioxide, a storage container operable to store a substance at a predetermined low tem-

perature, a liquid medium, conduit means containing said medium and adapted for natural convection circulation of said medium, a metallic plate having one end portion secured in heat exchange relation to said conduit means to remove heat from said medium and having the opposite end portion thereof secured in heat exchange relation with said first-named container, a second metallic plate having one end portion secured in heat exchange relation to said conduit means and having the other end portion secured in heat exchange relation to the top portion of said storage container on the wall thereof furthest away from said first-named container, and means for controlling the circulation of said medium so as to maintain a predetermined temperature in said storage compartment.

20. In an apparatus for controlling the flow of liquid, a member having a chamber, said member having an upwardly directed inlet aperture leading into said chamber and a downwardly directed outlet aperture leading from said chamber, and dam means positioned within and extending upwardly from the bottom wall of said chamber, said dam means extending across the interior of said member transversely to the flow passageway between said inlet and said outlet and forming a barrier over which the liquid must flow when flowing from said inlet aperture to said outlet aperture.

21. In an apparatus for controlling the flow of liquid, a member having a chamber, said member having a pair of oppositely disposed upwardly directed inlet apertures leading into said chamber and a pair of oppositely disposed downwardly directed outlet apertures leading from said chamber, one of said inlet apertures being

substantially parallel to one of said outlet apertures, the other of said inlet apertures being substantially parallel to the other of said outlet apertures, and dam means within said chamber and forming a barrier over which the liquid must flow when flowing from said inlet apertures to said outlet apertures.

22. In an apparatus of the character described, comprising a casing having a passageway therethrough, a weir means having a top face in said passageway, a chambered means, conduit means connecting the bottom portion of said chambered means to said passageway below the level of said top face, and a second conduit means connecting the top portion of said chambered means to said passageway above the level of said top face.

23. In an apparatus for controlling the flow of liquid, a member having an inlet chamber and an outlet chamber, said member having an upwardly directed inlet aperture leading to said inlet chamber and a downwardly directed outlet aperture leading from said outlet chamber, partition means within said member and forming a barrier over which liquid must flow from said inlet chamber to said outlet chamber, a second member for containing liquid, a conduit means having one portion opening into one of said chambers below the top surface of said partition means and having a second portion opening into said second member, and a second conduit means having one portion opening into said first-named member above said partition top surface and having a second portion opening into said second member.

LEWIS W. EGGLESTON.
